TABLE TOP IRONING MACHINE

Edward B. Carson, Fort Myers, Fla.

Application July 2, 1937, Serial No. 151,643

8 Claims. (Cl. 45—68)

This invention relates to table top ironing machines and has to do with means for mounting a box cover for movement into one of several positions, selectively.

5 In general, my invention is directed to an ironing machine comprising a hot shoe and a cooperating roll and a box cover positionable for enclosing the shoe and the roll, this cover also being positionable so as to be effective as a guard for 10 the hot shoe in the use of the machine, as well as positionable at one end of the machine to provide a readily accessible support for articles to be ironed and which have been ironed. More 15 specifically, my invention is directed to improved means for mounting the cover in such manner that it is capable of occupying any one of the several positions referred to, selectively. Further objects and advantages will appear from the detail description.

20 In the drawings:

Figure 1 is a plan view of an ironing embodying my invention, the cover being shown in open position effective as a guard for the hot shoe, other positions which this cover is capable of 25 occupying being indicated, this view being semi-diagrammatic;

Figure 2 is a back view of the machine of Figure 1, with the cover positioned as in the latter figure, the position of the cover at the end of 30 the machine being indicated in dot and dash lines;

Figure 3 is an end view of the machine of Figure 1 with the cover shown in full lines in the position which it occupies in the latter figure, 35 the position of the cover when closed being indicated in dot and dash lines;

Figure 4 is a lengthwise vertical sectional view 40 through the machine, taken in a plane adjacent the back thereof, with the cover in open position, and shown fragmentarily, parts being broken away and certain parts being shown in elevation, on an enlarged scale;

Figure 5 is a fragmentary sectional view taken 45 substantially on line 5—5 of Figure 4;

Figure 6 is a sectional view taken substantially on line 6—6 of Figure 4, on an enlarged scale, with the cover in closed position;

Figure 7 is a detail fragmentary sectional view, 50 on an enlarged scale, taken substantially on line 7—7 of Figure 4;

Figure 8 is a view similar to Figure 4, showing a modified form of my invention, the cover being shown partly in elevation and partly broken away;

Figure 9 is a fragmentary sectional view taken substantially on line 9—9 of Figure 8;

Figure 10 is a sectional view, on an enlarged scale, taken substantially on line 10—10 of Figure 8, certain parts being shown in elevation; 5

Figure 11 is a fragmentary detail sectional view taken substantially on line 11—11 of Figure 8, on an enlarged scale;

Figure 12 is a fragmentary detail sectional view taken substantially on line 12—12 of Figure 8, 10 on an enlarged scale, certain parts being shown in elevation.

My invention is in the nature of an improvement over the ironing machine disclosed in the Anderson and Janda Patent No. 1,656,656, dated 15 January 17, 1928, in that it provides means for disposing the cover in position effective as a guard for the hot shoe and further provides means whereby the cover, when not employed as a guard for the shoe, may be disposed at one end of the 20 machine and, if desired, in such position as not to project rearward beyond the bed of the machine.

I have illustrated my invention, by way of example, as applied to an ironing machine comprising supporting means in the form of a stand including a frame 15 and a bed plate 16 at the top of the frame, this bed plate having a depending peripheral flange 16a and being of channel section lengthwise and transversely. A gear 25 housing 17, of appropriate form and construction, is mounted at one end of the frame and extends downward through bed plate 16. A roll 18 projects from gear housing 17 lengthwise of bed plate 16 above and parallel with the latter, this roll being rotatably supported from gear housing 17 in an appropriate manner, conveniently in the manner disclosed in Patent No. 2,026,345, issued December 31, 1935, to Rudolph 30 W. Janda. A shoe 19 is disposed in rear of roll 18, parallel therewith and movable to and from the roll. Suitable means is provided for driving the roll and for operating the shoe and for releasing the latter, when required. Such means 35 may be similar to that disclosed in Patent No. 2,026,345, above referred to, and need not be shown nor illustrated in detail. Suffice it to state that suitable means is provided for operating the roll and the shoe and controlling operation thereof, the machine being driven by a prime mover, 40 conveniently an electric motor 20 appropriately mounted on the bed 16 and having driving connection to the mechanisms within the gear housing 17.

When the ironing machine is not in use the 55

- roll and the shoe, as well as the gear housing 17 above bed plate 16, are enclosed within a box-like cover 21 which seats, at its lower end, upon appropriately disposed rubber bumpers 22 secured to bed plate 16. Cover 21 is mounted so as to be capable of movement into any one of a plurality of positions, selectively, and my invention is directed particularly to the cover mounting.
- Referring to Figure 6, a bracket 23 is suitably secured, as by bolting, to the rear portion of gear housing 17, the upper arm of the bracket underlying one arm of a reinforcing angle member 24 disposed at the under face of bed plate 16 and extending lengthwise of the latter, and being secured to gear housing 17 by cap screws, one of which is shown at 23^a, passing upward through the upper arm of the bracket and through the upper arm of member 24 and bed plate 16.
- Bracket 23 extends downward and rearward of the machine and is provided, at its lower end, with a collar 24^a. An arm 25, of approximately S-shape in rear elevation, is pivotally mounted, at its outer lower end, on collar 24^a, by means of a pivot pin 26 passing through collar 24^a and arm 25 and appropriately confined against endwise movement. Arm 25 is thus pivoted, at its outer lower end, to the supporting structure of the machine for movement about an axis extending horizontally and perpendicular to the roll 18 and shoe 19.
- Arm 25 operates through a slot 27 in bed plate 16 extending lengthwise thereof and terminating adjacent the right hand end of the bed plate, as considered from in front of the machine, and in rear of and adjacent gear housing 17. In Figures 4, 5 and 6 arm 25 is shown in its normal inner position. In this position of the arm a bracket element 28, at the upper end thereof and comprising two spaced rearwardly projecting ears 29, is disposed a short distance above and parallel with the bed plate 16. Ears 29 receive a bar 30 square in cross-section fitting snugly through corresponding openings in ears 29 and lengthwise slidably through the latter. In this manner bar 30 is carried by arm 25 for movement therewith, is confined against turning movement about its axis relative to arm 25 and is capable of lengthwise sliding movement relative to the arm.
- Each end portion of bar 30 is reduced to provide a stud 31. A sleeve member 32 fits, at its inner portion, about bar 30 adjacent stud 31 and is there appropriately secured to the latter, as by means of a set screw 33. The sleeve member 32 is provided, at its outer portion, with a reduced bore which receives stud 31, this bore being in part defined by a cylindrical pivot element 34 projecting from the outer end of sleeve 32 concentric with stud 31. There is a sleeve 32 at each end of bar 30, as shown in Figure 4, and elements 34 of these sleeves extend through corresponding openings in appropriately formed brackets 35, welded or otherwise suitably secured to the back and the end walls of cover 21 adjacent the rear lower portion of the latter. In this manner cover 21 is pivotally mounted on bar 30 for movement about a horizontal axis extending lengthwise of bed plate 16, parallel to and in rear of the roll and the shoe, in the normal inner position of arm 25.
- Movement of bar 30 through ears 29 toward the right, as viewed in Figure 4, is limited by a stop, in the form of a screw 36, secured in the bar. When bar 30, together with the cover 21, has been moved into its extreme position toward the left hand end of bed 16, as considered from the front of the machine, or toward the right as viewed in Figure 4, cover 21 is then disposed so as to be positionable either over the roll and the shoe, in closed position, or along side the shoe in position to be effective as a guard therefor. Movement of cover 21 about the axis of bar 30 into position to enclose the roll and the shoe is limited by contact of the lower edge of the cover with the bumpers 22. Movement of cover 21 in opening direction is limited by contact of tabs 37, projecting from brackets 35, with fingers 38 rigid with and projecting upward from sleeves 32 a short distance from the outer ends thereof.
- An appropriately formed bracket 39 is secured at one end, conveniently by a screw 40, to bar 30. At its other end bracket 39 is provided with an opening which receives a rubber grommet 41 serving as a bumper to prevent marring of the upper surface of bed plate 16. This grommet receives, in the extreme position of bar 30 toward the right, as viewed in Figure 4, a rounded pin 42 secured through bed plate 16 by an associated nut 43. The height of bracket 39 is such that the bar 30 is held in horizontal position, in the normal inner position of arm 25. In this manner bracket 39 and pin 42 cooperate with arm 25 for holding bar 30 in parallel spaced relation to the upper face of bed plate 16, adjacent the rear thereof, while also confining the bar against endwise movement. With bar 30 in this position cover 21 is movable about the axis of the bar into either the open position shown in Figures 1 to 3, inclusive, or the closed position indicated by the dot and dash lines in Figure 3, in which closed position the cover encloses the roll and the shoe and so much of the gear housing 17 as extends above the bed plate 16.
- When cover 21 is turned into its open position shown in Figures 1, 2 and 3, it is disposed alongside the hot shoe in position effective to be a guard therefor. Positioning the cover in this manner, while of advantage in guarding the hot shoe may be disadvantageous, under certain conditions. For example, in small apartments having limited space, disposing the cover so as to project a considerable distance to the rear of the bed plate 16, when in open position, may cause the ironing machine to project an objectionable distance into the room from a wall thereof. This objection may be avoided by disposing the cover at one end of the ironing machine and so as not to project a considerable distance rearward of the bed plate, the ironing machine being then disposed with the back of the bed plate 16 adjacent a wall of the room thus guarding the hot shoe in a manner to prevent inadvertent contact therewith. Also, under appropriate conditions, as where the hot shoe is otherwise effectively guarded or no person other than the operator of the machine is present, the cover may be disposed at the end of the machine, projecting rearward thereof and providing means for supporting articles to be ironed and articles which have been ironed.
- Assuming that the cover 21 of the machine is in closed position, the ironing roll and shoe are effectively enclosed and shielded thereby and the top wall of the cover becomes available for use as a table. When it is desired to use the machine for ironing, the cover is turned about the axis of bar 30, as indicated by the arrow *a* in Figure 1, into open position. This exposes the cooperating ironing elements of the machine, which may now be used for ironing, the cover remaining in its open position shown in Figure 1, 75

if, desired. If preferred the cover 21 may be moved lengthwise, as indicated by the arrow b in Figure 1 and turned, with arm 25, about the pin 26 into vertical position at the end of the machine adjacent gear housing 17, extending rearward of the machine, as indicated by the dot and dash line in Figure 1. In this position of the cover the open side thereof is toward the front of the machine, the lower end of the cover is spaced above the floor and the upper end thereof is disposed a short distance above the gear housing 17, as will be clear from Figure 3, it being noted that movement of bar 30 through bracket 28, toward the left as viewed in Figure 4, is limited by a stop screw 45 secured in the bar. It will be understood that the bar may be provided with any suitable number of threaded bores for reception of screw 45, providing means for adjusting the position of cover 21, when the latter is disposed as indicated by the dot and dash lines in Figure 3, to any desired height within limits. In this position of cover 21 the end walls thereof are available for supporting articles to be ironed or articles which have been ironed. Rearward movement of cover 21 about the axis of bar 30, when disposed in the dot and dash position of Figure 1, is prevented by contact of tabs 37 with stop fingers 38. If desired, however, the cover 21 may be turned in a clockwise direction about the axis of bar 30, as indicated by the arrow b of Figure 1, into the dotted line position of this figure, the open side of the cover being then disposed toward and in proximity to the adjacent end of the bed plate 16. In this latter position of the cover the upper end thereof is available for supporting articles which have been ironed or are to be ironed. It will be noted that in the dotted line position of the cover, the latter does not project rearward of the bed plate of the machine which, therefore, may be disposed closely adjacent a wall of the room avoiding, where desirable, projection of the machine from the wall to an objectionable extent. The cover may be returned to closed position, after completion of the ironing, in an obvious manner.

When the cover is moved from horizontal position to vertical position, the arm 25 is swung from the full line position shown in Figure 4 to the dot and dash line position shown in this figure. Movement of arm 25 into its outer position is limited by one of the bumpers 22 disposed for contact with the lower edge of the head portion of the arm, when the latter occupies its outer position indicated in Figure 4. In this position of arm 25 bar 30 is disposed vertically and cover 21 is capable of movement about a vertical axis coincident with the axis of this bar, so as to be positionable in the manner above described.

In the modified form illustrated in Figures 8 to 12, inclusive, an arm 50 of approximately S-shape in rear elevation, formed as a stamping, is pivoted at its lower outer end on the pin 26. The upper portion of this arm is shaped to provide a bracket element 51. Headed studs 52 are secured through bracket element 51, adjacent the ends thereof, and project rearward therefrom. Rollers 53 are mounted upon studs 52 and are disposed within a channel bar 54 appropriately slotted, at its forward side, for reception of the studs and the rollers. Hinge brackets 56 are suitably secured, conveniently by welding, to the rearward face of bar 54 and fit between tabs 57 of plate 58 suitably secured, conveniently by welding, to the back wall of cover 21 adjacent

each end and a short distance above the lower edge thereof. A pintle 59 passes through tabs 57 and the arms of hinge bracket 56, thus hingedly connecting the cover 21 to bar 54, the pintle 59 being confined against endwise movement in an appropriate manner.

The rollers 53 facilitate lengthwise movement of bar 54 and cover 21, relative to arm 50. Such movement of the bar, in either direction, is limited by stop members 60 secured within bar 54 by means of screws 61 and associated nuts 62. The left hand stop member 60, as viewed in Figure 8, is so disposed as to contact the left hand roller 53, when bar 54 is in its normal position shown in this figure. A bracket 63 has its upper portion extended into the channel of bar 54, adjacent the right hand hinge bracket 56, and secured to the bar in a suitable manner, conveniently by welding. A rubber grommet 64 is mounted in the lower end of bracket 63, providing a rubber bumper and also cooperating with a rounded pin 42 for confining bar 54 against endwise movement, in the manner previously described with reference to Figure 7.

In the normal position of arm 50 bar 54 is disposed lengthwise of bed plate 16, parallel therewith and a short distance thereabove. Cover 21 is then supported for turning movement about the common axis of pintles 59, adjacent and parallel to the bar 54. In the closed position of cover 21, enclosing roll 18 and shoe 19 and so much of the gear housing 17 as extends above bed plate 16, the rear wall of the cover is disposed vertically as shown in full lines in Figure 10. In order to expose the roll and shoe and associated parts of the machine, for ironing, cover 21 is swung downward and rearward into its open position, indicated by the dot and dash lines in Figure 10, in which position the rear lower edge portion of the cover contacts the lower face of bar 54, limiting opening movement of the cover and holding it in position alongside the hot shoe where it is effective as a guard for the shoe. The cover and bar 54 may be moved lengthwise of the latter, by raising bracket 63 slightly so as to disengage it from the pin 42, and, together with arm 50, may be swung about pin 26 so as to dispose the cover in vertical position at the end of the machine adjacent the gear housing 17, in the same manner as previously described. When the cover is thus vertically disposed, downward movement thereof is limited by a contact of the upper stop member 60 with the upper roller carried by arm 50, this arm then occupying the position indicated by the dot and dash lines in Figure 8. Obviously, the bar 54 may be provided with an appropriate number of suitably spaced openings whereby the stop member 60 may be variably positioned for adjusting the cover at any desired height, within limits, when it is disposed vertically adjacent the end of the machine. It will also be understood that any other suitable means for limiting lengthwise movement of the bar with respect to its associated arm, may be provided.

As above indicated, and as will be understood by those skilled in the art, changes in construction and arrangement of parts of my invention may be resorted to without departing from the field and scope of the same, and I intend to include all such variations, as fall within the scope of the appended claims, in this application in which the preferred forms only of my invention have been disclosed.

I claim:

1. In combination, a stand having a top bed plate, an arm pivoted on said stand for movement into and out of normal position from and to a second position, about a horizontal axis adjacent one end of said bed plate and extending transversely thereof, a bar carried by said arm disposed adjacent the rear of and parallel to said bed plate in the normal position of said arm, said bar being disposed vertically in said second position of said arm, a box cover, and means pivotally connecting said cover to said bar for movement about an axis parallel therewith and movement lengthwise of said bar relative to said arm, whereby said cover may be lowered at said end of said bed plate and turned about said latter axis into either of two positions substantially at right angles one to the other, when said arm is in its said second position.
2. In combination, a stand having a top bed plate provided adjacent one end with a lengthwise slot, an arm projecting through and operating in said slot pivoted at its lower end to said stand on a horizontal axis extending transversely of said bed plate, said arm being capable of occupying a normal position and a second position perpendicular to its normal position and having at its upper end a bracket element disposed above said bed plate in the normal position of said arm, a bar carried by said bracket element disposed lengthwise of and parallel to said bed plate in the normal position of said arm, said element having means supporting said bar for relative lengthwise sliding movement, a box cover and means pivoting said cover at its rear lower portion on said bar and confining it against lengthwise movement relative thereto.
3. In combination, a stand having a top bed plate provided adjacent one end with a lengthwise slot, an arm projecting through and operating in said slot pivoted at its lower end to said stand on a horizontal axis extending transversely of said bed plate, said arm being capable of occupying a normal position and a second position perpendicular to its normal position and having at its upper end a bracket element disposed above said bed plate in the normal position of said arm, a bar carried by said bracket element, the latter having means supporting said bar for lengthwise sliding movement therethrough and confining it against relative turning movement, said bar being disposed lengthwise of and parallel to said bed plate in the normal position of said arm, a box cover, means pivotally mounting said cover at its rear lower portion on said bar for turning movement thereabout, and supplementary means limiting rearward movement of said cover about said bar.
4. In combination, a stand having a top bed plate provided adjacent one end with a lengthwise slot, an arm projecting through and operating in said slot pivoted at its lower end to said stand on a horizontal axis extending transversely of said bed plate, said arm being capable of occupying a normal position and a second position perpendicular to its normal position and having at its upper end a bracket element disposed above said bed plate in the normal position of said arm, spaced supports projecting from said bracket element, a channel bar lengthwise slidable on said supports and disposed lengthwise of and parallel to said bed plate in the normal position of said arm, a box cover, and means pivotally connecting said cover at its rear lower portion to said bar for movement about an axis parallel therewith.

5. In combination, a stand having a top bed plate provided adjacent one end with a lengthwise slot, an arm projecting through and operating in said slot pivoted at its lower end to said stand on a horizontal axis extending transversely of said bed plate, said arm being capable of occupying a normal position and a second position perpendicular to its normal position and having at its upper end a bracket element disposed above said bed plate in the normal position of said arm, spaced rollers projecting from said bracket element toward the rear of said bed plate, a channel bar receiving and lengthwise slidable on said roller disposed lengthwise of and parallel to said bed plate in the normal position of said arm, a box cover, and means pivotally connecting said cover at its rear lower portion to said bar for movement about an axis parallel therewith.

6. In combination, a stand having a top bed plate provided with a lengthwise slot terminating adjacent one end thereof, an arm of substantially S-form projecting through and operating in said slot pivoted at its lower end to said stand on a horizontal axis extending transversely of said bed plate, said arm being capable of occupying a normal position and a second position perpendicular to its normal position and having at its upper end a bracket element disposed above said bed plate in the normal position of said arm, a bar carried by said bracket element disposed lengthwise of and parallel to said bed plate in the normal position of said arm, the latter having means supporting said bar for relative lengthwise movement, a box cover, and means pivotally connecting said cover at its rear lower portion to said bar for movement about an axis parallel therewith.

7. In combination, a stand having a top bed plate, a box-like cover for covering said bed plate, hinge means connecting said cover to said stand at the back and adjacent one end thereof, said hinge means comprising a first horizontal pivot disposed above and parallel to the back edge of said bed plate when the cover is closed, about which the cover is movable upward and rearward from closed to open position, and a second horizontal pivot extending in a direction from front to back of said bed plate, said first horizontal pivot being connected to said second horizontal pivot for pivotal movement about the latter, said cover being movable with said first horizontal pivot from open position into a second position at said end of said stand perpendicular to its open position, and means supplementary to said hinge means mounting said cover for relative movement lengthwise of said first pivot for lowering of said cover, when it is in said second position at said end of said bed plate.

8. In combination, a stand having a top bed plate, a box-like cover for covering said bed plate, and hinge means connecting said cover to said stand at the back and adjacent one end thereof, said hinge means comprising a first horizontal pivot disposed above and parallel to the back edge of said bed plate when the cover is closed, about which the cover is movable upward and rearward from closed to open position, and a second horizontal pivot extending in a direction from front to back of said bed plate, said first horizontal pivot being connected to said second horizontal pivot for pivotal movement about the latter, said cover being movable with said first horizontal pivot from open position into a second position at said end of said stand substantially perpendicular to its open position.
